UNITED STATES PATENT OFFICE.

WILLIAM C. COLLIGNON, OF CHICAGO, ILLINOIS.

PNEUMATIC ACTION.

1,403,591.

Specification of Letters Patent. Patented Jan. 17, 1922.

Application filed January 19, 1921. Serial No. 438,289.

To all whom it may concern:

Be it known that I, WILLIAM C. COLLIGNON, a citizen of the United States, residing at Chicago, in the county of Cook and State 5 of Illinois, have invented certain new and useful Improvements in Pneumatic Actions, of which the following is a specification.

This invention relates to pneumatic actions especially adapted for mechanically 10 operated keyboards, such as in automatic pianos, the operation of which is controlled by a perforated sheet, or record strip moving over a perforated tracker board.

Another object is to provide an efficient 15 structure that may be made and assembled at a low cost.

Another object is to provide an improved 20 valve which will automatically adjust itself on its seat, and to provide an improved seat that is not materially affected by accumulation of dust.

Another object is to provide an improved 25 guide for the valve stem.

Other, further and more specific objects 30 of the invention will become readily apparent, to persons skilled in the art, from a consideration of the following description, when taken in conjunction with the drawings, wherein:—

Fig. 1 is a central vertical section through 35 a pneumatic action, and a wind-chest that may be common to a plurality of such actions.

Fig. 2 is a section taken on line 2—2 of 40 Fig. 1 looking in direction of the arrows.

Fig. 3 is an enlarged central section through the valve, and its ports and ducts.

Fig. 4 is a bottom plan view of one of the 45 pneumatic actions, looking in direction of the arrows on line 4—4 of Fig. 1.

In all the views the same reference characters are employed to indicate similar parts.

A casing 5, preferably of wood, extends 50 the full length of a series of actions which are to be mounted thereon in spaced-apart relation.

A plate 6 covers the casing 5 and is preferably of metal; such, for example, as aluminum or the like.

Casing 5 is provided on each of its longitudinal edges with a laterally extending 55 flange, 7 and 8, respectively, and it is also channeled, as at 9, to provide a wind-chest, or vacuum chamber, and, at intervals along the length of the wind-chest, it is provided with depressions in its floor or pouch cham-

bers 10, that are to be located immediately below each of the pneumatic actions. These pouch chambers are in communication with the wind-chest 9 through an opening 11 60 which is covered by a diaphragm, or puff, 12.

Each of the actions is provided with an inclined block 13 and mounted upon which is a plate or lever 14, pivoted as at 15, and between the plate 14 and the block 13 is a 65 bellows fold 16. In the block 13 is a valve chamber 17 which communicates with the interior of the bellows 16 through a duct 18. The interior of the bellows and the duct 18 is normally open to the atmosphere through 70 another duct 19.

The cover plate 6 is perforated at intervals to provide an opening between the valve chamber 17 and the wind-chest 9, these openings are located immediately below each of 75 the pneumatic actions. Each of the openings 20, thus provided, is spanned by a bridge 21 which affords a guide for the valve stem 22. In each instance the bridge 21 is pushed below the surface 23 which serves 80 as an annular seat for the valve 24. The valve 24 and its stem 22 are made, preferably, of a single piece of wood, fiber or the like.

The upper surface 25 of the valve 24 is 85 convex and at its apex carries a vertically positioned pin 27. Surrounding the pin and comprising the supporting portion of the valve 28 is a, preferably, metal disk 29, having a central perforation 30, somewhat 90 larger than the diameter of the pin 27.

Secured to the upper surface of the metal disk 29 is a soft yielding sheet 31, like kid, chamois, or the like, adapted to be seated against the surface 32, comprising the valve 95 seat and made at the lower end of the duct 19.

Secured to the bottom surface of the valve 24 is a similar material 33 adapted to be seated on the valve seat 23 provided in the cover plate 6.

Mounted on the puff diaphragm 12 is a weight 34 upon the upper surface of which rests the valve stem 22. The covering 31 of the valve 28 fits neatly to the pin 27, so that the valve 28 may freely be rocked upon 105 the upper surface 25 of the valve 24, whereby valve 28 will always automatically find its seat 32, when it is raised and into contact therewith.

The valve 28 is shown mounted upon a 110 washer 36 that surrounds the pin 27.

The vent tube 37 leads to the tracker board,

as usual in structures of this character, and the tube 38 is the means by which the wind-chest 9 is exhausted. The sticker rod of the piano rests upon the outer end of the lever 14 and these move the wippines of the usual piano action. (These parts of the structure are not shown as they do not constitute any portion of applicant's improved structure).

Each of the piano actions 6 is secured to the casing 5 by means of screws 38 and 39 passing through the flanges 7 and 8, respectively, and a packing strip 40 is placed between the upper surface of the flanges and the lower surface of superposed cover board, or plate, 6.

The use and operation of the device will be readily understood by persons versed in the art.

While I have herein shown a single embodiment of my invention for the purpose of clear disclosure, it will be manifest, to persons skilled in the art, that changes may be made in the general arrangement and configuration of the parts within the scope of the appended claims.

Having described my invention what I claim as new and desire to secure by Letters Patent, is:—

1. In a pneumatic action, a valve structure providing a convex support; a pin extending vertically from the apex of said support; a centrally perforated disk surrounding the pin and overlying the support, the perforation permitting the disk to be rocked freely on the support; a flexible covering overlying one side of the disk and neatly fitting the pin, and a port to be closed by the valve.

2. In a pneumatic action, a valve structure providing a convex support; a pin extending vertically from the apex of said support; a centrally perforated disk surrounding the pin and overlying the support, the perforation permitting the disk to be rocked freely on the support; a flexible covering overlying and cemented to the upper side of the disk and neatly fitting the pin; a port to be closed by the valve disk and a guide for said support.

3. In a pneumatic action, the combination with a casing containing a wind-chest and a pouch chamber communicating therewith; a cover plate closing the wind-chest and having an opening therein overlying said pouch chamber; a bridge spanning said opening to form a guide for a valve stem, said bridge

vertically displaced below the upper surface of said opening to provide an uninterrupted valve seat; a valve covering the seat; a puff diaphragm overlying said pouch chamber; a weight on the diaphragm and a valve stem extending from the valve, through the opening in the bridge and terminating near said weight.

4. In a device of the character described, a casing containing a channel for a wind-chest; a depression below the floor thereof to provide a pouch chamber; a vent pipe, for connection with a tracker board, communicating with the pouch chamber; a puff diaphragm overlying the opening between the pouch chamber and said channel; an opening in the cover plate, immediately above the diaphragm; a bridge spanning the opening, vertically displaced below the upper surface of the plate bounding the opening to provide an uninterrupted valve seat; said bridge having an opening for guiding a valve stem, a valve for closing said opening; a valve stem extending through the bridge and terminating near the diaphragm therebelow, said valve having an upper convex surface; a pin extending vertically from and above the apex of said surface; a disk, overlying the pin, having a central hole permitting the disk to be rocked freely thereon; a sheet of yielding material overlying the disk and neatly fitting the pin; a pneumatic action having a valve port overlying said disk valve and a pipe through which to exhaust the wind-chest.

5. A casing having longitudinally extending flanges on each side; a channel between the flanges to provide a wind-chest; a series of spaced-apart depressions made in the floor of the channel to provide pouch chambers; a duct below the channel leading into the chamber to vent the latter; a puff diaphragm secured to the floor of the channel and covering the pouch chambers, one for each chamber; a cover plate overlying said channel, having an opening over each diaphragm; a pneumatic action having a port overlying each opening in the cover and a double valve operable by the puff diaphragm for alternately closing a port in said pneumatic action device and opening a port in said cover plate.

In testimony whereof I hereunto subscribed my name.

WILLIAM C. COLLIGNON.
